UNITED STATES PATENT OFFICE.

SAMUEL KRISKA, OF LORE CITY, OHIO.

RAIL-CLAMP AND METALLIC TIE.

1,383,406.

Specification of Letters Patent.

Patented July 5, 1921.

Application filed April 20, 1921. Serial No. 463,087.

To all whom it may concern:

Be it known that I, SAMUEL KRISKA, a citizen of the United States, residing at Lore City, in the county of Guernsey and State 5 of Ohio, have invented certain new and useful Improvements in Rail-Clamps and Metallic Ties, of which the following is a specification, reference being had to the accompanying drawings.

10 It is the purpose of the present invention to provide an improved rail clamp for use in connection with metallic ties, particularly of the type herein illustrated, though it is obvious the clamp may be used in connection 15 with other forms of metallic ties.

Still another purpose is to provide an improved clamping means for the rails, comprising channels or key ways extending transversely of the tie, to receive wedges or 20 tapered keys, for passing through rail anchoring members or keys, to clamp the rails in position.

25 A further purpose consists in the provision of means carried by fish plates for the reception of the heads of the rail anchors or keys, to prevent movement of the rails longitudinally.

30 While the design and construction at present illustrated and set forth is deemed preferable, it is obvious that as a result of a reduction of the invention to a more practical form for commercial purposes, the invention may be susceptible of changes, and the right to these changes is claimed, provided they 35 are comprehended within the scope of what is claimed.

The invention comprises further features and combination of parts, as will be herein-after set forth, shown in the drawings and 40 claimed.

In the drawings:

Figure 1 is a plan view of the improved metallic tie, showing the improved rail clamp and joint applied.

45 Fig. 2 is a longitudinal sectional view on line 2—2 of Fig. 1.

Fig. 3 is a sectional view on line 3—3 of Fig. 1.

50 Fig. 4 is a bottom plan view of the metallic tie.

Fig. 5 is a detail perspective view of one of the rail anchors 12.

Fig. 6 is a perspective view of the cotter pin.

55 Referring to the drawings, 1 designates a metallic tie, which may be of any suitable pro-

portions, preferably beveled on its sides and ends as shown, with its under surface hollowed or chambered out, so that the ballast or bed of the road will engage up into the 60 chamber of the tie, to assist in preventing creeping. The tie may be cast, though it may be otherwise formed, and the hollowed or chambered out under surface is provided with longitudinally and transversely extending intersecting webs 2 and 3, which coöperate with the flanges 4 and 5 of the beveled sides and ends of the tie, to additionally assist in preventing creeping. The flanges 4 are cut away as shown at 6, so as 65 to permit the ballast to engage with the flanges, to additionally prevent creeping.

Also cast integral with the under surface of the tie are transversely disposed ribs 7 having channels or key ways 8, which receive the wedges or tapered keys 9. The keys or wedges extend through the channels or key ways, so that their tapers assume positions in opposite directions. Formed integrally with the ribs 7 are enlargements 10, 75 which are hollowed out, and these chambers 11 are intersected by the channels or key ways 8. The enlargements 10 are diagonally disposed, there being one on each side of each rail. The chambers 11 of the enlargements receive rail anchors 12, which are provided with openings 13, through which the keys 9 pass. The keys 9 are tapered, and their smaller ends are provided with offset slots 14, either one of which of each key 90 receives a cotter pin 15, constructed of sheet spring metal, to hold the keys 9 in position, and thereby holding the anchors in place. The upper ends of the anchors 12 are provided with heads 16 to overlie the bases of 95 the rails, thereby holding the rails from displacement upwardly. The adjacent ends of two rails 17 which are connected together by the fish plates 18, have bolts 19 passing through the fish plates and the rails, to connect the parts together.

The base flanges of the fish plates on diagonally opposite sides of the rails have notches 20 for the reception of the heads 16 of the anchors, which not only anchor the 105 rails upon the tie, but also act to anchor the rails against longitudinal movement, due to engaging the notches 20 of the bases of the fish plates. The upper surface of the tie adjacent both ends thereof has ribs 21, 110 which are spaced equal to the width of the bases of the rails, so that the bases of the

rails may engage therebetween. These ribs are positioned, according to the spacing of the rails, to insure holding the rails in position.

5 The invention having been set forth, what is claimed as being useful is:

1. A rail anchor comprising in combination with a metallic tie having spaced transversely disposed key ways or channels and 10 provided with diagonally disposed vertical pockets intersecting the channels, rail anchor members engaging the pockets and having heads overlying the base of the rail to hold the rail in position, and keys or wedges passing through the key ways or channels and 15 intersecting the anchors to hold them in the pockets, and means for holding the keys in the channels or key ways, fish plates for connecting two adjacent rails, said fish plates having notches to be engaged by the heads of the anchors, to prevent longitudinal 20 movements of the rails.

2. In a rail anchor, the combination with a metallic tie having upon its under surface

spaced transversely disposed ribs connecting the sides of the tie, said ribs having key ways or channels formed therethrough and opening through or at the outer faces of the sides of the tie, said ribs also having cast therewith enlargements provided with pockets 30 intersecting the channels, said enlargements and their pockets being diagonally opposed, of rail anchors corresponding with and fitting said pockets and having openings registering with the channels or key ways, and provided with heads overlying the base of a rail at diagonal opposed positions, wedges engaging through the channels or key ways, the taper of said wedges extending in opposite directions, the smaller ends of the wedges 35 having a plurality of openings, and cotter keys engaging through certain of said openings of the wedges to hold them in different positions, thereby holding the rail anchors in place, and retaining the rail in position. 40 45

In testimony whereof I hereunto affix my signature.

SAMUEL KRISKA.
